STRAINER-EQUIPPED CONDENSATION
DRAINER

Charles W. St. Clair, Painesville, Ohio, assignor to
The Coe Manufacturing Company, Painesville,
Ohio, a corporation of Ohio

Application April 11, 1951, Serial No. 220,478

1 Claim. (Cl. 137—177)

1

This invention relates to condensation draining devices for the removal of condensate from pipe lines or other apparatus to which steam or vapor is being supplied. More particularly, this invention relates to a condensation drainer of the continuous type embodying a permanently open flow control orifice and which is an improvement over the drainers disclosed in United States Patents 1,950,227 granted March 6, 1934 and 2,020,563 granted November 12, 1935.

An object of the present invention is to provide an improved condensation drainer of the type embodying a permanently open orifice and a strainer for preventing clogging of the orifice, and in which novel mounting means is employed for positioning the strainer in the desired location.

Another object is to provide an improved condensation drainer of the character mentioned in which the novel mounting means permits the strainer to be readily removed for inspection or cleaning and renders the strainer self locating when being replaced, and in which the closure means for the strainer access opening will always have fluid-tight engagement therein and will insure proper positioning of the strainer regardless of repeated removal and replacement of such closure means.

A further object is to provide an improved condensation drainer of the kind above referred to in which the strainer is an open-ended foraminous sleeve and the mounting means comprises axially spaced internal annular seat means engaged by the ends of the sleeve and having a self-centering effect thereon.

The invention can be further briefly summarized as consisting in certain novel combinations and arrangements of parts hereinafter described and particularly set out in the claim hereof.

In the accompanying sheet of drawings:

Fig. 1 is an outside elevational view showing a condensation drainer embodying the present invention.

Fig. 2 is a longitudinal vertical section taken through the drainer of Fig. 1, substantially on the vertical longitudinal mid-plane thereof; and

Fig. 3 is a fragmentary vertical section corresponding with a portion of Fig. 2 and showing the strainer and the strainer mounting means on a larger scale.

As representing one practical embodiment of the invention, the drawing shows the improved condensation drainer 10 as comprising a metal body or housing 11 having an inlet portion 12

and an outlet portion 13. The inlet portion 12 is provided with an inlet passage 14 for admitting condensate or a mixture of condensate and steam under pressure and is adapted to be connected with a pipe coil or other steam using apparatus as by means of the conduit 15. The outlet portion 13 is provided with an outlet passage 16 for the discharge of condensate from the drainer and is adapted to have a discharge conduit 17 connected therewith for conducting the condensate to a hot-well, waste drain or other disposal place.

The inlet portion of the drainer 10 is also provided with a condensate and sediment collecting chamber 18 which is formed by a pair of serially connected, laterally adjacent branch portions comprising a down-flow branch portion 19 and an up-flow branch portion 20. These down-flow and up-flow branch portions have their lower ends connected by a short connecting passage 21. One of these branch portions, preferably the down-flow branch 19, constitutes a strainer chamber in which a strainer 22 is mounted by the novel strainer mounting means 23 to be described hereinafter.

The inlet passage 14 can, if desired, be connected directly with the down-flow branch 19 but as shown in Fig. 2 is preferably connected with the upper portion of the down-flow branch 19 through a receiving chamber 23. This receiving chamber is located directly above the down-flow branch 19 and is separated therefrom by an intervening transverse wall 24 of the housing 11. The lower end of the receiving chamber 23 is connected with the upper end of the down-flow branch 19 through a relatively short connecting passage 25 of the wall 24.

The outlet portion of the drainer 10 is provided with an evaporating chamber 26 and a discharge chamber 27. The discharge chamber 27 is disposed in an upright laterally adjacent relation to the up-flow branch 20 of the inlet portion of the drainer. The outlet passage 16 is in open communication with the discharge chamber 27 for conducting condensate freely therefrom. The evaporation chamber 26 is an intermediate chamber having portions thereof located above the up-flow branch 20 and the discharge chamber 27.

The flow of condensate through the drainer 10 is controlled by an orifice fitting 28 and a tube 29, which are mounted in transverse wall portions 30 and 31 of the housing 11. The orifice fitting 28 contains a permanently opened restricted flow control orifice 28a forming a con-

necting passage between the upper end of the up-flow branch 20 and the evaporation chamber 26. The tube 29 has a permanently open passage 29^a which connects the evaporation chamber 26 with the discharge chamber 27.

For convenience in inspecting or replacing the orifice fitting 28 and the tube 29, the housing 11 is provided with suitable openings 32 and 33 located above these members and which are normally closed by suitable screw plugs 34 and 35. The discharge chamber 27 is provided at the lower end thereof with a drain opening 36 which is normally closed as by means of a removable plug 37.

In the operation of the improved drainer 10, a mixture of condensate and vapor under pressure is supplied to the collecting chamber 18 through the receiving chamber 23 and the passage 25. The vapor supplied to the receiving chamber 23 comes in contact with the extensive internal wall surface thereof and is condensed into liquid which unites with the condensate entering through the inlet passage 14 and flows directly into the collecting chamber 18 through the passage 25 and the down-flow branch 19. Before passing into the up-flow branch 20 through the connecting passage 21, the condensate must travel through the screen 22 by which scale, rust or other sediment will be removed and prevented from causing clogging or abrading of the orifice fitting 28.

Under the pressure of the steam of the conduit 15, the condensate is forced upwardly into the up-flow branch 20 and is discharged through the orifice 23^a into the evaporation chamber 26 from which the condensate flows downwardly through the tube 29 into the discharge chamber 27 and then out into the conduit 17 through the outlet passage 16. The condensate which collects in the chamber 18 and that which is forced upwardly in the up-flow branch 20 forms a liquid seal for the orifice fitting 28 to prevent steam from being wastefully discharged through the orifice 23^a and the passage 29^a of the tube 29. The flow of condensate through the orifice fitting 28 is a somewhat pulsating flow but nevertheless a more or less continuous flow by which the condensate will be effectively removed from the apparatus served by the drainer 10, at substantially the rate of production of such condensate. The theory of operation for this type of drainer is described in greater detail in the above-mentioned earlier Patent No. 1,950,227.

The novel mounting means for the strainer 22 constitutes an important part of this invention and will be described next. As shown in Figs. 2 and 3, the strainer 22 is an elongated, tubular strainer or foraminous sleeve extending axially in the down-flow branch 19 of the collecting chamber 18. The lower end of the down-flow branch 19 is provided with an opening 38 through which the strainer 22 can be inserted or removed and through which condensate and sediment can be drained from the collecting chamber 18. The opening 38 is provided with an internal screw thread which, for the purposes of this invention, is a tapered pipe thread, and is adapted to be closed by a plug 39 having stem portion 39^a also provided with a tapered pipe thread and engaging in such opening.

The strainer 22 is positioned in the down-flow branch 19 by the engagement of the ends of the strainer with upper and lower seat means provided on the wall 24 and on the plug 39. As shown in Fig. 3 of the drawing, the upper seat means for the strainer 22 comprises a substan-

tially flat annular surface 40 provided on the underside of the wall 24 in surrounding relation to the passage 25 and adapted to be engaged by the upper end 22^a of the strainer. The upper seat 5 means also includes a relatively short substantially cylindrical internal annular locating surface 41 located immediately adjacent the flat seat 40 and which may be formed as a counterbore extending into the wall 24. This internal annular surface 41 snugly embraces the upper end 22^a of the strainer and positions the same in the down-flow branch 19. Additionally, the upper seat means includes a tapered approach portion 10 leading to the internal annular locating surface 41 and defined by an upwardly converging internal annular tapered surface 42.

The lower seat means for the strainer 22 is formed on the plug 39 which supports the strainer in the down-flow branch 19. The stem portion 20 39^a of the plug is provided with an axial recess 43 which receives the lower end 22^b of the strainer. The upper portion of the recess 43 comprises a relatively short cylindrical portion defined an internal annular locating surface 44 of the stem 25 39^a of the plug. The lower end 22^b of the strainer extends into the cylindrical portion of the recess 43 and is snugly embraced by the internal annular surface 44. The lower portion of the recess 43 is a tapered portion defined by a downwardly converging internal annular surface 45 which forms 30 a supporting seat for the lower end 22^b of the strainer.

When the strainer 22 is to be assembled into the housing 11 its lower end 22^b is inserted into the recess 43 of the plug 39. The strainer and plug assembly thus formed is moved upwardly axially of the strainer chamber 19 and during which movement the strainer 22 is inserted into this chamber and the threaded stem portion 39^a of the plug is screwed into the opening 38. The strainer 22 is of a length such that when the plug 39 has been tightly engaged in the opening 38, the upper end 22^a of the strainer will engage the flat seat 40 and the lower end 22^b of the strainer will engage the tapered seat 45.

During the insertion of the strainer 22 into the chamber 19, the upper end of the strainer will automatically center itself by the guiding action thereon of the tapered approach portion 42 such that the upper end of the strainer will quickly 50 come into proper engagement with the seat 40 without jamming. During the tightening of the plug 39, this member will lift the screen 22 so as to press and retain the upper end thereof against the seat 40 and the tapered lower seat 45 will 55 exert a self-centering action on the lower end of the screen. By reason of the mounting means just described above for the screen 22, it will be seen that this member can be easily and rapidly assembled into the housing 11 and will result in 60 the screen being always correctly positioned and retained in the housing.

Because of the tapered pipe thread provided in the opening 38 and on the plug 39 this plug, when tightened in the opening will always form 65 a fluid-tight closure therein. Repeated removal and replacement of the plug 39 will result in some wear on the threads, but the tapered shape of the plug causes this wear to be taken up by the plug moving somewhat farther into the opening 70 38. Such further movement of the plug into the opening 38 to always form a fluid-tight closure therein is permitted by the intervening space provided between the housing 11 and the head of the plug. So far as the strainer 22 is concerned, 75 this increased inward movement of the plug 39

into the opening 38 is accommodated by relative sliding between the lower end of the strainer and tapered annular guide surface 45 of the plug.

From the accompanying drawing and the foregoing description, it will now be readily understood that this invention provides an improved condensation drainer of the continuous type which embodies a strainer and novel mounting means for such strainer. Since the orifice passage in a drainer of this kind may be of very small diameter such as could easily become clogged, the strainer and the strainer mounting means represent an adjunct of real importance. It will also be seen that by reason of the novel strainer means herein provided, the assembly of the strainer in the drainer can be very easily accomplished and the locating and retention of the strainer in the proper position is always assured.

Although the novel strainer mounting means provided by this invention has been illustrated and described herein to a somewhat detailed extent, it will be understood of course, that the invention is not to be regarded as being limited correspondingly in scope, but includes all changes and modifications coming within the terms of the claim hereof.

Having thus described my invention, I claim:

A condensation drainer comprising, a housing having an inlet portion adapted to be connected with a source of condensate and vapor under pressure and an outlet portion including a low pressure outlet chamber, said inlet portion having therein a vapor chamber and a condensate chamber in laterally adjacent relation and an upright strainer chamber connecting the lower end of said vapor chamber with the lower end of said condensate chamber, the lower ends of said strainer and condensate chambers forming a pocket for the collection of condensate and sediment and the lower end of said strainer chamber being provided with an opening, means defining a permanently open restricted flow control orifice connecting the upper end of said condensate chamber with said outlet chamber, a transverse

wall in said housing between said vapor chamber and said strainer chamber and forming an upper strainer seat, a substantially cylindrical internal annular locating surface in said strainer chamber immediately adjacent said upper strainer seat, an upwardly converging internal annular surface in said strainer chamber forming a tapered approach for said locating surface and upper strainer seat, a closure plug engaged in said opening and having a recess in the upper side thereof surrounded by a wall defining an upwardly convergent axially tapered lower annular strainer seat, and an open-ended substantially cylindrical strainer extending axially in said strainer chamber and supported therein by said plug with the upper end of said strainer engaging said upper strainer seat and embraced by said annular locating surface and the lower end of the strainer extending into the recess of said plug and engaging said tapered lower strainer seat, said tapered approach and said tapered lower seat being effective on said strainer for centering the same during assembly thereof in said housing, said opening having an axially inwardly converging tapered pipe thread therein and said closure plug also having an axially converging pipe thread thereon for fluid-tight engagement with the pipe thread of said opening, said closure plug being movable into said opening for an increased distance to compensate for wear on said pipe threads.

CHARLES W. ST. CLAIR.
